UNITED STATES PATENT OFFICE

ERNEST GREMMINGER, OF MILL VALLEY, CALIFORNIA

ROTARY SPRING STUFFING BOX

Application filed May 6, 1929. Serial No. 360,901.

My invention relates to improvements in rotary spring stuffing boxes, and it consists in the combinations, constructions and arrangements hereinafter described and 5 claimed.

In certain types of machines that pump gases, it is absolutely essential to prevent the escape of these gases from the machine and this is especially true if the gas is poisonous.

10 The principal object of my invention is to provide means for trapping the gas at the place where it is most likely to leak out—that is, at the shaft bearing. I employ centrifugal force for trapping the gas.

15 A further object of my invention is to provide a device of the type described which makes use of novel means for automatically taking up wear in the sealing mechanism. The device can also be used for preventing 20 flow of air into the machine as well as preventing the leaking of the gas out of the machine.

Other objects and advantages will appear 25 in the following specification, and the novel features of the device will be particularly pointed out in the appended claims.

My invention is illustrated in the accompanying drawings forming a part of this application, in which

30 Figure 1 is a longitudinal section through one form of the device; and

Figure 2 is a section through a modified form.

In carrying out my invention, I make use 35 of a pump shaft 1 which may be driven by a pulley 2 or other suitable means. The shaft passes through a wall of a casting 3 as shown in the drawing and is journaled in roller bearings, indicated generally at 4, (see Figure 1).

The gases within the casting 3 will have a tendency to pass between the casting 3 and a ring 5. In normal practice, the ring is spaced away from an opening 6 in the casting and it is through this space that the gases 45 leak.

The gases pass around the roller bearings 7 and on into a compartment 8 formed by a housing 9 that is secured to the casting 3 by 50 means of bolts 10 or other suitable fastening

means. The shaft 1 carries a collar 11 that is threaded on to the shaft at 12 and rotates therewith.

Novel means is provided for trapping the 55 gas in the compartment 8.

It will be noted that the housing 9 has an inwardly-extending flange 13 and that a cup-shaped member 14 is rotatably mounted in the housing and is operatively connected to the collar 11 so as to rotate therewith. The 60 means connecting the cup-shaped member 14 to the collar 11 comprises a pin 15 that is slidably received in a slot 16 in the collar 11. The slot permits longitudinal movement of the pin, but carries the pin around with the shaft. In this way, the cup member 14 will rotate in the housing 9 when the shaft 1 rotates.

The bottom 17 of the cup 14 is held against the flange 13 by means of a spring 18. This 70 spring bears against the collar 11 and against the bottom of the cup. The cup is provided with an opening 19 in its bottom for receiving the shaft 1 and this opening is sealed from the compartment 8 by a diaphragm 20. The ends of this diaphragm 75 bear against a ring 21 secured to the collar 11 and a ring 22 secured to the bottom of the cup 17.

An annular groove 24 is formed at the bottom of the housing 9, and passageways 25, formed in the cup 14, lead from the interior of the cup to the groove 24.

From the foregoing description of the various parts of the device, the operation thereof may be readily understood.

As already stated, the gas will tend to pass into the compartment 8 where it will be rotated, due to the rotating collar 11.

This will cause the gas to move outwardly, 90 due to centrifugal force, and a portion of it will pass between the cup 14 and the housing 9 and into the annular groove 24. Some of the gas will pass on into the cup 14, then through the passages 25 and on to the groove 24. The rapidly-rotating gas in the groove 24 will be prevented from moving inwardly along the inside of the flange 13 because of 95 centrifugal force. The gas will therefore be trapped in the compartment 8 and in the 100

groove 24 and will gradually build up in pressure until this pressure counterbalances the pressure of the gases flowing into the compartment 8. It will be seen therefore that a rapid rotation of the gases and the trapping of them will prevent any leakage.

The spring 18 constantly keeps the cup 14 seated on the flange 13 and is designed to automatically take up wear between the cup and the flange. The diaphragm 20 expands as the cup is moved toward the flange 13 and therefore will always provide a perfect seal between the compartment 8 and the opening 19.

15 In Figure 2, I show a slightly modified form of the device. In this form, the air outside of the machine is prevented from gaining access thereto, as well as the gas within the machine is prevented from leaking out. A shaft 50 is rotatably mounted in a casting 51 and is journaled in roller bearings 52. The gases within the machine will tend to pass through a passageway 53 and then on into a compartment 54. A cup member 55 bears against a flange 56 of a housing 57 and is held thereagainst by a spring 58. A sleeve 59 is threaded on the shaft 50 at 60 and rotates with the shaft.

30 The cup 55 also rotates with the shaft and is operatively secured to the sleeve 59 by a set screw 61 carried by the sleeve and entering a slot 62 in the cup 55. This construction causes the cup to rotate with the sleeve.

35 The gases will be rotated in the compartment 54 and will pass on into an annular groove 63 in the housing 57. At this point, they will either be trapped by centrifugal force or may flow into the interior 64 of the cup. Through an outlet 65, the interior of the cup may be connected with the interior of the machine for guiding the trapped gases back to the latter.

40 Air is prevented from entering the machine by a structure similar to that already described, but disposed in a reverse order. The housing 57 has a portion 66 that is secured thereto by bolts 67 or other suitable fastening means. The portion 66 has a flange 68, and a cup-shaped member 69 is rotatably mounted in the portion 66 and bears against the flange 68, due to the force of the spring 58. The cup 69 is rotated by the shaft 50. It will be noted that a ring 70 is secured to the cup 69 and that the ring is operatively connected to the shaft by a set screw 71, which in turn is secured to a member 72 that is keyed to the shaft.

45 Rings 73 and 74 are secured to each other and to the sleeve 59. A ring 75 is secured to the cup 55 and a diaphragm 76 is disposed between the rings 73 and 75. A second diaphragm 77 is disposed between the rings 70 and 74. These two diaphragms prevent any leakage of gas from the cups and also pre-

vent any passage of air from within the diaphragms to a place within the cups.

50 The air entering an opening 78 and the portion 66 will tend to flow into a groove 79 in the portion, due to centrifugal force, and then be trapped. This trapping of the air prevents it from passing on into the machine. I have already set forth how the gas is prevented from leaking from the machine and it will therefore be seen that the form of the device shown in Figure 2 will prevent gas from leaking out of the machine and air from passing into the machine.

55 The stuffing boxes shown in the two figures are spaced from the shafts so as to clear them. The stuffing boxes will therefore not be affected by vibration of the shaft nor by the expansion of the latter through heat.

60 Although I have shown and described two embodiments of my invention, it is to be understood that the same is susceptible of various changes, and I reserve the right to employ such changes as may come within the scope of the appended claims.

65 I claim:

1. The combination with a shaft, of a housing encircling said shaft and having an inwardly-extending flange, a cup-shaped member slidably mounted within said housing and rotatable on the flange, yielding means for keeping the cup seated on the flange and a diaphragm sealed to the shaft and to the cup.

70 2. A stuffing box comprising a housing for encircling a shaft, said housing having an inwardly-extending flange at each end thereof and a pair of rotatable members mounted in said housing for causing a medium within the housing to be thrown to the wall by centrifugal force and to be trapped by said flanges and spring means for keeping said rotatable members in yielding contact with said flanges.

75 3. A stuffing box comprising a housing for encircling a shaft, said housing having an inwardly-extending flange at each end thereof and a pair of rotatable members mounted in said housing for causing a medium within the housing to be thrown to the wall by centrifugal force and to be trapped by said flanges, spring means for keeping said rotatable members in yielding contact with said flanges and a diaphragm sealing the shaft and the rotatable members against a fluid passing therebetween.

80 4. A stuffing box comprising a housing having an inwardly-extending flange, a cup-shaped member rotatably mounted in said housing and having an opening in its bottom, means for rotating the member, means for forcing the member against said flange, said housing having a shaft centrally disposed thereof and extending through said cup-shaped member and a diaphragm sealing the shaft and the interior of the cup-shaped

member for preventing the flow of a fluid into the cup-shaped member.

5. A stuffing box comprising a housing for encircling a shaft, said housing having an inwardly extending flange at each end thereof and a pair of rotatable members mounted in said housing and snugly bearing against said flanges for causing a medium within the housing to be thrown to the wall by centrifugal force and to be trapped by said flanges.

10. A stuffing box for a shaft comprising a housing for receiving an escaping medium from a machine, said housing having an inwardly extending flange and a recess formed in the latter, a rotatable member mounted in said housing for causing the medium therein to be centrifugally thrown into the recess, and yielding means for urging the member into contact with the flange, whereby the 15 medium in said recess will form a seal between the flange and the rotating member.

15. A stuffing box comprising a housing for receiving a medium leaking from a machine, said housing having an inwardly extending flange and a recess formed in the latter, and a rotatable cup-shaped member mounted in said housing and bearing against said flange, said cup-shaped member having apertures 20 leading from the interior thereof and communicating with said recess, the medium in said housing being centrifugally forced through said apertures and into said recess when the cup-shaped member is revolved.

25. A stuffing box comprising a housing for receiving a medium, said housing having an inwardly extending flange at each end thereof and recesses formed in the latter, and a pair of rotatable members mounted in said housing and bearing against said flanges for 30 causing the medium within the housing to be centrifugally thrown against the wall thereof and into the recesses.

35. A stuffing box comprising a housing for receiving a medium, said housing having an inwardly extending flange at each end thereof and recesses formed in the latter, rotatable members mounted in said housing and bearing against said flanges for centrifugally throwing the medium in the housing against 40 the wall thereof and into the recesses, and a spring disposed between said members for urging the latter into contact with said flanges.

ERNEST GREMMINGER.
